SAFETY CONTROL FOR PRESSING MACHINES

Frank C. Lornitzo, Pawtucket, R. I., assignor to
Pantex Pressing Machine, Inc., Central Falls,
R. I., a corporation of Delaware

Application October 28, 1940, Serial No. 364,287

26 Claims. (Cl. 38—40)

My invention relates to improvements in safety controls for pressing machines, preferably to pressing machines adapted for use in pressing garments and having fluid pressure actuated operating means.

An object of my invention is to provide a safety control for a pressing machine wherein both hands of the operative are occupied until the pressing members have been brought into pressing juxtaposition and in which a separate handle is provided for each hand movable for actuating purposes in a single direction only and preferably also so constructed that in case one of the hands should slip off, movement of one handle alone will automatically cause the device to separate the pressing members so that there is no possibility of accident to the other hand. In my preferred embodiment each handle is actuated in the same direction to close the pressing machine, the actuation of one handle only in the same direction being operable to open the pressing machine to separate the pressing members so that there can be no possibility of accident.

A further object of my invention is to further insure the safety of the operator's hands by providing a latch which will not only not latch to keep both hands occupied until both manual means are each moved to an actuating position, but also one which will not take effect until they are then conjointly released, thereby keeping the operator's hands occupied until a definite mental step is necessary to effect the actuation of the latch.

As an additional safety feature, the pressing machine is preferably so constructed as to employ only a relatively light pressure while bringing the members into pressing juxtaposition, which pressure immediately changes to a relatively higher ironing pressure after there is no danger of the hands being caught between the pressing members.

A further feature of my invention is to provide means automatically operated by gravity and controlled by the pressing member actuating means when said pressing members are brought into pressing juxtaposition to permit release of the handles at substantially the instant when the device changes from the application of a light to heavy ironing pressure, thereby freeing the operator's hands for other uses during the application of the heavy ironing pressure.

A further feature of my invention is to provide the handles in a hidden and yet accessible place where they will not catch on the clothes being pressed and for this purpose I preferably

locate them immediately underneath the front end of the usual table and provide guard means, such as a downturned flange at the front of the table to protect the handles.

5 Further features of my invention relate to improvements in the control means for controlling the flow of fluid to the fluid motor for bringing the pressing members into pressing juxtaposition.

One specific feature of the control means is that I employ a quick acting flush valve to rapidly exhaust the fluid motor to separate the pressing members, located in the feed line to the fluid motor, preferably immediately adjacent the fluid motor. To actuate said quick acting flush valve to quickly evacuate the fluid motor, I also provide a bleeding trigger exhaust valve in said feed line and an inlet valve in said feed line and suitable means to effect opening of said inlet valve and closing of said trigger exhaust valve substantially simultaneously to actuate the fluid motor and closing of said inlet valve and opening of said trigger exhaust valve substantially simultaneously, the trigger exhaust valve functioning to release the quick acting flush valve in the same feed line to immediately evacuate the motor. If the quick acting flush valve be not employed, or should fail in use, it is obvious that the exhaust valve itself may evacuate the fluid motor in a slower manner.

20 A further object of my invention is to simplify the control means for the fluid motor by employing the inlet valve and the bleeding trigger exhaust valve in a single master valve with each valve controlled by a single stem member. So far as I am aware this feature is new whether the quick acting flush valve be employed in combination with the master valve, or otherwise.

25 A further feature of my invention resides in the fact that both the inlet and exhaust valves of the master valve and the inlet and the exhaust portions of the quick acting flush valve are self-closing so that in order to cause actuation of all of said valves simultaneously to actuate the fluid motor to bring the pressing members into pressing juxtaposition, or to evacuate said fluid motor to separate said pressing members, a single movement of the movable control member in a single direction only is necessary, in the embodiment shown, the movable control member and the various valves being self-movable to positions evacuating the fluid motor when the movable control member is no longer restrained or moved to a position actuating the fluid motor to bring said pressing members into pressing juxtapositions.

Due to the aforescribed construction employing the quick acting flush valve, it is obvious that I am able to provide a preferably two-hand, manual control for the master valve, which same two-hand control functions as a remote control through the medium of the flow of fluid through the feed line for the quick acting flush valve and it is thus apparent that I have provided a single manual control for actuating all of the valves employed in the system.

A further feature of my invention relates to the fact that I employ a check valve in combination with the quick acting flush valve, inlet valve and bleeding trigger exhaust valve in the feed line whether or not said check valve, inlet valve and bleeding trigger exhaust valve are associated together in a master valve, preferably a check valve of a self-closing type so that in case a plurality of pressing machine units are operated from a single source of fluid pressure, each one may be operated independently without affecting the operation of the other, particularly in a manner to insure that the operation of one pressing machine in the series will not affect the safety features of the improved control means for the other pressing machines. With the employment of a check valve it is obvious that the safety feature in each of the units will be maintained in the case of failure of the common source of fluid supply.

A further feature of my invention is to provide a mechanism wherein each step changing the phase of operation of the device takes place with a sharp and positive actuation. For this purpose I preferably provide the various types of check, inlet and exhaust valves employed with positive self-closing features so that the transition from open to closed position will take place rapidly. For the same reason I preferably employ a gravity actuated latch which will tilt sharply into a latching position. It is obvious that the instant actuation of a gravity actuated latch is highly desirable in the event the addition of a timing mechanism to the pressing machine is desired.

A further feature of my invention is that by the provision of such self-closing valves and a gravity actuated latch I am able to provide a mechanism which will function more quickly than prior art mechanisms which depended for their similar actuation on the relatively slow movement of the fluid in the cylinder.

Further features of my invention relate to improvements in the detailed construction of the handle operated actuating means, the specific construction of the quick acting flush valve, the specific construction of the master valve and the specific construction of the various parts of my invention to make them practical for use in a specific type of fluid motor actuating means for bringing the pressing members of a garment pressing machine into pressing juxtaposition and later applying a greater ironing pressure, the various parts of my invention being particularly constructed to cooperate with a linkage system for bringing the pressing members into pressing juxtaposition, including a link pivotable on one fulcrum to bring said members rapidly to a pressing position with relatively light pressure and pivotable after a predetermined amount of its movement on a different fulcrum to automatically apply a greater predetermined ironing pressure to said pressing members.

A further feature of my invention is to provide a latch which will be jam-proof without danger of breaking the various parts thereof.

Further features of my invention relate to the specific construction of the various valves which make the feed line for the fluid motor substantially leak proof, particularly the specific construction of the leak-proof master valve.

These and such other objects of my invention as may hereinafter appear will be best understood from a description of the accompanying drawings which illustrate embodiments thereof applied to a garment pressing machine.

In the drawings,

Fig. 1 is a diagrammatic view with the various valve portions or means to control the fluid motor in a static position maintaining the pressing members in open position and illustrating a side elevation of a garment pressing machine showing the feed line at right angles thereto with the quick acting flush valve and master valve including the control member thereof in section and the actuating handles therefor in elevation at right angles to said control member, the parts being so distorted as to illustrate diagrammatically the operation of the device.

Fig. 2 is a view similar to Fig. 1 after both of the handles have been jointly actuated to move the control member into a position actuating the fluid motor to bring the pressing members into pressing juxtaposition.

Fig. 3 is a view similar to Fig. 1 after the latch means has functioned to latch the parts in the position shown in Fig. 2, to permit further actuation of the fluid motor to apply the ironing pressure and the release of the handles if desired during the application of the ironing pressure.

Fig. 4 is a view similar to Fig. 1 illustrating, in dotted lines, the actuation of a single handle to release the control member from the latch to permit the quick acting flush valve to quickly evacuate the fluid motor to separate the pressing members.

Fig. 5 is a cross sectional view taken along the line 5—5 of Fig. 2.

Fig. 6 is a cross sectional view taken along the line 6—6 of Fig. 2.

Fig. 7 is a cross sectional view taken along the line 7—7 of Fig. 3.

Fig. 8 is a cross sectional view taken along the line 8—8 of Fig. 3.

Fig. 9 is an end elevation of the front portion of the end of the pressing machine with the parts in the position shown in Fig. 1, particularly illustrating the handles, the master valve and the specific means for controlling the operation of said master valve through manipulation of said handles.

Fig. 10 is a front elevation of the parts of the pressing machine shown in Fig. 9.

Fig. 11 is a diagrammatic view illustrating the master valve in side elevation and in perspective an alternative type of handles and means actuated thereby for controlling the actuation of the master valve specifically including an axially movable wire encased in a flexible cable for purposes of remote control.

Fig. 12 is a diagrammatic view similar to Fig. 3 of an embodiment of my invention modified in two particulars, namely, with the latch actuated by the cylinder and positively actuated by the motion of the cylinder instead of by gravity and constructed to be jam-proof.

Fig. 13 is a fragmentary view of a portion of the operating lever and latch shown in Fig. 12, illustrating how the positive connection between the cylinder and latch is yieldable to prevent

Jamming of the latch and consequent breaking of the parts in use.

In the drawings, wherein like characters of reference generally indicate like parts throughout, I have shown my invention applied to a standard type of garment pressing machine 20. Said pressing machine includes the relatively movable pressing members 22 and 24, in the embodiment shown, comprising the usual stationary buck 22 mounted on the pressing machine above the usual table 26 and the movable pressing head 24 pivotally mounted on the machine frame 28 as at 30, in the embodiment shown, being mounted on the end of the power arm 34 of a lever of the first class 32 having a weight arm 36 extending rearwardly therefrom, weighted to normally pivot the pressing head 24 to an open position.

Suitable means are provided for moving the movable pressing head 24 into pressing juxtaposition with the buck 22, including a fluid motor 38 and means controlled by the fluid motor 38 for moving said lever 32 for this purpose, in the preferred embodiment shown, comprising the specially constructed linkage 40. Means are provided for controlling the flow of fluid to said fluid motor 38, including a feed line 42 for said fluid motor, an inlet valve 44 in said feed line and an exhaust valve 46 in said feed line and means to effect opening of said inlet valve 44 and closing of said exhaust valve 46 substantially simultaneously to actuate said fluid motor 38 to pivot said pressing head 24 into pressing juxtaposition over the buck 22 and alternatively to close said inlet valve 44 and open said exhaust valve 46 substantially simultaneously to evacuate said fluid motor 38 to permit said weight arm 36 to pivot said pressing head 24 away from said buck. In order to quickly evacuate the fluid motor to permit rapid movement of the pressing head 24 away from the pressing buck 22 I also interpose in said feed line, preferably adjacent said fluid motor a quick acting flush valve 48 and where said quick acting flush valve is employed, the exhaust valve 46 becomes a trigger exhaust valve to cause a drop of pressure in said feed line 42 beyond said trigger exhaust valve 46 to cause the actuation of the flush valve 48 in the automatic manner to be explained. If desired, however, the quick acting flush valve 48 may be dispensed with, but if it be employed, a trigger exhaust valve 46 in the feed line is necessary to initiate the actuation of the quick acting flush valve 48 in the manner to be explained. Where a plurality of pressing units 20 are actuated by a single source of fluid supply, I also preferably employ in the feed line 42, a check valve 50 to prevent actuation of one unit from affecting the actuation of the other pressing units 20 in the system. While I have shown my invention applied to a garment pressing machine, it may be employed in any type of a pressing machine, such as a metal stamping machine, or a plastic molding machine and insofar as the controlling features of my invention are concerned, the specific type of control shown may be employed to control a fluid motor 38 to actuate any type of a movable member, whether it be the pressing head 24, or any other movable member in an entirely different type of machine.

A further feature of my invention, which is particularly desirable in pressing machines, is that of locating the bleeding trigger exhaust valve 46, the inlet valve 44, and the check valve 50, where employed, in a master control valve 52, the movement of all three of these valves being controlled by the movement of a single stem mem-

ber 54. In the embodiment shown, the inlet valve 44 is of a self-closing type, the check valve 50 is of a self-closing type and the bleeding trigger exhaust valve 46 is of a self-closing type with the self-closing check valve 50, the self-closing inlet valve 44 and the self-closing bleeding trigger exhaust valve 46 being so arranged in the master valve 52 that a single movement of the control member 54 in one direction is all that is necessary allowing line pressure to respectively open the inlet valve 44, open the check valve 50 and permit self-closing of the trigger exhaust valve 46, the stem member 54 being normally spring urged to a position opening the exhaust valve 46 and permitting self-closing of said inlet valve 44 and check valve 50. The master valve 52 is thus so constructed that a single movement of the stem member 54 away from its self-closing position will function to allow line pressure to open the inlet valve 44, open the check valve 50 and permit self-closing of the bleeding trigger exhaust valve 46. As explained, the quick acting flush valve 48 is automatically self-opening when a drop in pressure occurs in the feed line 42 due to opening of the bleeding trigger exhaust valve 46. One feature of my invention is that the master valve is substantially leak-proof for the self-closing of the exhaust valve 46 takes place just prior to the actual opening of the inlet valve 44 and the self-closing of the inlet valve 44 takes place just prior to the opening of the exhaust valve 46.

In the preferred form of master control valve 52 shown, said valve is provided with a chamber 56, and the feed line 42 includes an inlet line 58 connecting said chamber 56 with the source of fluid pressure supply and an outlet line 60 connecting said chamber 56 with the fluid motor 38, or with the quick acting flush valve 48 where employed. The inlet valve 44 is provided at the inlet port of said chamber 56, the bleeding trigger exhaust valve 46 is also provided in said chamber 56 and the control member 54 also is movable from a closed position in said chamber 56 free of said inlet valve 44 and retaining said exhaust valve 46 in open position to an open position opening said inlet valve 44 and permitting closing of said exhaust valve 46. Means such as the operating lever or control member 62 operable from without said master control valve is provided to move said stem member 54 to said open position and spring means 116 is provided to normally urge said stem member 54 to a self-closing position when said operating lever 62 is free. As also stated, in the preferred embodiment shown, the inlet and check valves 44 and 50 are of a self-closing type, the bleeding trigger exhaust valve 46 is also of a self-closing type and the stem member is normally urged to a closed position opening said exhaust valve and permitting self-closing of said inlet and check valves 44 and 50. It is thus obvious that said operating lever or control member 62 can be moved to an open position from without said master valve 52 against the spring pressure normally retaining it and said stem member 54 in closed position, moving said stem member 54 to a position opening said inlet valve 44 and permitting self-closing of said exhaust valve 46 and that the means normally urging said stem member to a closed position will automatically function when pressure is removed from said operating lever or control member 62 to move said operating lever and stem member back to a closed position opening the exhaust valve 46 and permitting self-

closing of said inlet and check valves 44 and 50. In the preferred embodiment shown, my preferred type of master control valve is preferably constructed as follows: Said valve includes a casing 64 (Fig. 1) having a chamber 66 divided into an inlet chamber 66 and an exhaust chamber 68. Said inlet chamber 66 has an inlet port 70 connected by the pipe 58 to the source of fluid pressure supply and a check valve seat 72 surrounding said inlet port 70. The exhaust chamber 68 is connected to said fluid motor 38, or to said quick acting flush valve 48 by the pipe 60, as explained. The partition 74 extends between said inlet chamber 66 and said exhaust chamber 68 and is provided with suitable passage means 76 connecting said inlet and exhaust chambers 66 and 68. The exhaust chamber is provided with the exhaust valve branch 78 and the operating lever branch 80 projecting radially therefrom, in the embodiment shown, being in diametric alignment. The inlet valve 44 comprises an inlet valve seat 82 preferably of frusto-conical shape in the lower end of said inlet chamber 66 around the upper end of said passage means 76. The check valve 50 includes a hollow cylindrical valve guide socket 84 having a side wall 86 slidably mounted in the cylindrical upper chamber 66 at a spaced distance from the wall 88 thereof by means of the annular flanges 90 rigidly mounted at spaced distances on said chamber wall and provided with the plurality of perforations 92 therein as shown in Fig. 5. Said valve guide socket 84, in the embodiment shown, is provided with a conical upper end 94 forming the check valve 50 normally extending within said inlet port 70 at a spaced distance from the wall thereof and slidable to a closed position on said check valve seat 72 closing said inlet port 70. Said guide socket 84 is also provided with the open lower end 96 located immediately above said inlet valve seat 82. Spring means 98 comprising the helical spring 98 is contained within said socket 84. The inlet valve 44 comprises a suitable valve, in the embodiment shown, a ball valve normally urged to a seated position on said inlet valve seat by said seating spring means. Said seating spring means 98 also functions to normally move said socket 84 to seat its conical upper end 94, comprising the check valve 50 in a self-closing manner on its check valve seat 72. In the embodiment shown, said passage means 76 comprises a cylindrical bore 100 of substantial diameter at the upper end thereof and a plurality of passages 102 flaring radially outwardly and downwardly to discharge in the upper end of said lower exhaust chamber 68 (Fig. 6).

An inlet valve stem 54 is provided for vertical reciprocation within said exhaust chamber 68. Said valve stem 54 has an upper end 104 adapted to about said ball inlet valve 44 to raise it against the pressure of the spring 98 to unseat said ball inlet valve 44 to open said inlet valve. Said valve stem 54 is provided at a point intermediate the ends thereof with the flange means 106 projecting radially therefrom, in the preferred embodiment comprising a disk 106. The valve stem 54 is reciprocably mounted in said exhaust chamber 68 with the upper end 104 extending through said passage bore 100 and into said inlet valve chamber 66 to unseat said ball inlet valve 44. Means are provided to vertically align said valve stem for vertical reciprocation within said exhaust chamber 68 and passage means 76, in the preferred embodiment, said means comprising a hollow stud 108 having a central bore 110 dis-

charging into said passage bore 100 for containing the upper end of said valve stem 54 and projecting vertically downwardly from the upper end of said exhaust chamber 68 between the lower ends of said radial passages 102. Said aligning means also includes, in the embodiment shown, a hollow stud 112 projecting externally downwardly from said casing 64 having a bore 114 to receive the lower end of said stem 54. A helical spring 116 is provided in said lower exhaust chamber 68 abutting said disk 106 or flange means and the upper wall of said lower chamber between said radial passages 102 to normally urge said valve stem member 54 to closed position free of said inlet valve 44 to permit the normal self-closing or seating of said inlet valve 44 and said check valve 50 by said expansion seating spring means 98.

A self-seating exhaust valve 46 is provided in the exhaust valve branch 78 of said exhaust chamber 68. Said exhaust valve 46 includes a peripheral shoulder 118 projecting radially inwardly in the inner end of said exhaust branch 78 and an exhaust port 120 in the outer end of said exhaust branch 78 having an exhaust valve seat 122 at the inner end thereof, in the embodiment shown of frusto-conical shape. The exhaust valve proper 46 has a surface 124 seatable on said exhaust valve seat, in the preferred embodiment, comprising a partially spherical surface 124 to cooperate with said frusto-conical valve seat 122. In the embodiment shown, the exhaust valve 46 has an annular disk 126 perforated as at 127 projecting radially outwardly therefrom as shown in Fig. 7 terminating in an outwardly projecting peripheral flange 130. An exhaust valve stem 132 projects inwardly from said valve 46 terminating in an inner end 134 preferably spherically enlarged, as shown, contacting the disk 106 of said inlet valve stem 54. Spring means, such as the helical spring 136 is provided in said exhaust branch 78 surrounding said valve stem 132 and having an inner end abutting said peripheral shoulder 118 and an outer end abutting said perforated exhaust valve disk 126 to normally urge said exhaust valve 46 to a seated position on its valve seat 122 with the peripheral flange 130 abutting the outer end of said exhaust branch 78 exterior of said exhaust port 120 when the enlarged inner rod end 134 is free of said inlet valve stem disk 106.

Said master valve also includes an operating lever or control member 62 nonleakably universally pivotally mounted in the end wall 140 of said operating lever branch 80 having an inner end 138, preferably spherically enlarged, as shown, underlying said inlet valve stem disk 106. For this purpose, a port 142 is provided in the end wall 140 of said outlet branch having an outwardly diverging wall 144 and a partially spherical socket 146 in the inner end thereof. In the embodiment shown, the outwardly diverging portion 144 comprises a separate extension from the outer wall 140 of said operating lever branch 80. The control lever 62 has a spherical pivot enlargement 148 centrally thereof seated in said partially spherical socket 146 for universal movement of said control lever therein. The enlarged spherical inner end 138 of said control lever 62 contacts said valve stem disk 106. The outer end 150 of said operating lever or control member thus projects outwardly through and beyond the outwardly diverging internal wall 144 of said outlet port 142 or extension 152, through and beyond the end of said port or extension 152 abutting the wall 75 of said port or extension to limit the universal

movement of the outer end 150 of said operating lever or control member 62. To render the operating lever branch leak-proof I preferably provide a sealing spring washer 154 having a central hole 156 adapted to overlie the inner end of the spherical enlargement 148 to normally urge it outwardly to continuously abut and cover the inner surface of said spherical lever pivot portion 148 to positively prevent leakage of air through said port 142 into said operating lever branch 80.

Any suitable type of means may be provided to operate said master control valve by the depression of the outer end 150 of said operating lever or control member 62. The exhaust valve branch 78 exterior of said exhaust port 120 may be provided with suitable sound deadening means 158, such as felt, or otherwise, to muffle the changes in the flow of air through said valve.

As stated hitherto, I preferably employ a quick acting flush valve 48 interposed in said feed line 42 beyond said trigger exhaust valve 46. Said flush valve includes a chamber 160 having an inlet port 162, an outlet port 164 and an exhaust port 166, an exhaust valve 168 to close said exhaust port 166 normally urged to an open position, an inlet valve 170 connected to said exhaust valve controlled by a drop of pressure from said inlet port 162 caused by bleeding of said trigger exhaust valve 46 to permit back pressure from said fluid motor 38 to rapidly close said inlet port 162 and open said connected exhaust valve 168 and a self-closing combination check and differential valve 172 in front of said exhaust valve 168 and in rear of said inlet valve 170 to prevent back pressure in said line 42 and effective on sustained pressure in said line to admit fluid pressure through to said fluid motor 38.

In the preferred embodiment, said quick acting flush valve is preferably constructed as follows: The chamber 160 is divided into an upper exhaust portion 174 and a lower inlet portion 176 connected by the passage means 178. The inlet chamber 176 has the inlet port 162 in the lower wall thereof connected to the exhaust chamber 68 of said master valve by the pipe portion 60 of said feed line 42. The exhaust portion 174 has the outlet port 164 therein and the exhaust port 166 therein in vertical alignment with the inlet port 162 in said inlet chamber 176. The exhaust port 164 is connected to said fluid motor 38 by the pipe 180 forming part of the inlet or feed line 42. The exhaust port 166 is provided with the exhaust valve seat 182, preferably of partially spherical shape extending around said exhaust port. The valve stem 184 is mounted for vertical reciprocation within said chamber 160 and projects vertically upwardly through said inlet chamber 176, said passage means 178 and said exhaust chamber 174. Said valve stem 184 is provided with the inlet valve 170 on the lower end thereof adjacent said inlet port 162 comprising in the preferred embodiment shown, a disk valve 170 of substantially the circular or other area of said inlet chamber 176 adjacent said inlet port 162 having a plurality of vents 186 therein exterior of said inlet port 162 preferably arranged in annular formation exterior of said inlet port 162 as shown in Fig. 8 providing a solid central portion 188 for sealing said inlet port 162 to provide an inlet valve. The exhaust valve 168 is mounted on the opposite end of said stem 184 in said exhaust chamber 174 and preferably comprises a spherical valve 168 adapted to seat in said partially spherical valve seat 182 surrounding said exhaust port 166. It is apparent

that fluid pressure from said inlet line 42, on opening of said inlet valve 170, will raise said flush valve inlet valve 170, said connected valve stem 184 and said connected exhaust valve 168 to a position closing said exhaust port 166 and that said inlet valve 170, connected valve stem 184 and said connected exhaust valve 168 will drop on reduction of pressure in said feed line to open said exhaust port 166 and close said inlet port 162. I also provide a combination check and differential valve 172 in said inlet chamber 176 preferably of flat annular formation and of a size to seal said vent means 186 in said inlet valve 170. I also provide spring means 190 in said chamber 160 abutting said check valve 172 of a strength to normally urge said check valve 172 to a position sealing said inlet vents 186, namely, with said check valve 172 covering and closing said vent means 186, said spring means 190 being yieldable, however, to permit sustained pressure in said line to raise said check and differential valve 172 against the pressure of said spring 190 to permit fluid to flow through said vent means 186 around said spring 190 in said inlet chamber 176 through said passage means 178 and out through said outlet port 164 and through said pipe 180 to actuate said fluid motor 38. Exhausting of pressure in said feed line 42 due to opening of said bleeding trigger exhaust valve 46 will inevitably permit lowering of said inlet valve 170, valve stem 184 and connected exhaust valve 168 to permit rapid evacuation of fluid from said fluid motor 38 through said pipe 180, outlet port 162, exhaust chamber 174 and exhaust port 166. In the embodiment shown the other end of the spring abuts the lower surface of the ball exhaust valve 168. If desired, the entire flush valve may be inverted.

As stated hitherto, I believe the novel features of structure of my improved quick acting flush valve are also novel. As also stated hitherto, it is apparent that insofar as certain aspects of my invention are concerned, the quick acting flush valve 48 may be omitted if desired.

As stated hitherto, my invention also includes safety means, including a pair of handles 192 for actuating the fluid or other motor employed to bring the pressing members 22 and 24 into pressing juxtaposition. Features of my invention reside in the facts that the handles 192 are only effective on a single movement thereof in a single direction to affect the controlling means for the fluid motor and that they are operable to actuate the controlling means for the motor to bring said members 22 and 24 in pressing juxtaposition only when both of said handles 192 are moved together, movement of one of said handles 192 only being operable to affect said controlling means to separate said pressing members. It is thus obvious that during the dangerous period of relative movement of said pressing members 22 and 24 to pressing juxtaposition, both of the operator's hands are employed on the respective handles 192 to cause such movement and that if anything should happen causing the removal of a hand from one of the handles, the device will automatically function to positively effect relative opening movement of said pressing members.

A further desirable feature of my preferred embodiment therefore is that each of the actuating means is moved in the same direction to release to safety position as to move the device to a pressing position, both of the handles, however, being required to effect movement of the ma-

chine to a pressing position. Insofar as this feature of my invention is concerned, it is apparent that any type of motor may be employed to move the members 22 and 24 to and from pressing positions. As stated hitherto, I preferably employ the fluid motor 38 for this purpose. As most types of pressing machines are provided with a table 26, I have found that an ideal place for the mounting of the handles is below the front end of said table where they will not catch upon the clothes or other material being operated on. The respective handles 192 are preferably provided of a relatively large area so that they may be accessible from various points along the front of the machine. If desired, guard means, such as the flange 194 (see Fig. 9) projecting integrally downwardly from the front end of the table 26 may be provided to further protect the handles. Any suitable type of handles, however, may be employed, such as the operating buttons 192' shown in Fig. 11, each of which actuates an axially slidabile wire 196 encased in a suitable protective armored cylindrical flexible casing 198. The type of handles or buttons shown in Fig. 11 are particularly desirable when remote control over a machine at a distance is desired, or a plurality of machines assembled to operate as a unit are employed. As stated, one feature of my invention consists in the fact that movement of both handles in a single direction is required to actuate the controlling means to bring the pressing members into pressing juxtaposition and while movement of one handle only is preferably employed to release said members from pressing juxtaposition, other types of means to release said members or to evacuate the fluid motor for this purpose, such as shown in my co-pending application for patent on Control means for pressing machines, Ser. No. 376,286, filed January 28, 1941, may be employed. While any type of means may be employed to move the movable stem member 54 to actuate the inlet valve 44 and the exhaust valve 46 and any type of means for controlling the motor or the flow of fluid to a fluid motor may be employed with my improved handles just described, best results may be obtained when my improved handle means are employed to regulate the inlet valve 44 and exhaust valve 46 through the movement of the movable stem member 54 in association with the specific controlling means shown and to be described. In the embodiment shown, both the fluid flow controlling means and the handle means for controlling the movement of the movement control member 54 are particularly designed to cooperate with each other for use in a garment pressing machine and hence, in the preferred embodiment shown, the respective handles 192 are designed and constructed to actuate the movable stem member 54 of the master valve 52 through the medium of the operating lever or control member 62. When employed for this purpose, the respective inlet valve 44, check valve 50 and trigger exhaust valve 46 are preferably self-closing in the manner previously described, so that when both handles 192 are not actuated, the operating lever 62 will be immediately released to a safety position closing the inlet valve 44 and opening the outlet valve 46 permitting immediate separation of said pressing members 22 and 24.

Another feature of my improved combination is that I preferably provide in combination with the handles, or other manually operated means hitherto described, means preferably comprising gravity actuated latch means 200 automatically

controlled by the actuating means for bringing the pressing members 22 and 24 into pressing juxtaposition, substantially when said pressing members 22 and 24 have been brought into pressing juxtaposition, to permit said controlling means to continue to function to permit actuation of said fluid motor to apply ironing or other pressure without further actuation of said respective handles 192, freeing the hands for other uses on other machines, if desired, while the ironing pressure is being applied.

Any means may be provided to release the movable control member 62 to free it from said latch 200 to exhaust the fluid motor 38 to separate said pressing members.

If desired, means may be provided to bring said members 22 and 24 to a pressing position with relatively light pressure and to automatically apply a greater predetermined ironing pressure to said pressing members after they have been brought into pressing juxtaposition. My invention is particularly applicable to a pressing machine employing this greater ironing pressure, for not only are both hands kept occupied during the dangerous period of bringing the members into pressing juxtaposition, but also said members are brought together with relatively light pressure during this dangerous period. To achieve this result I preferably employ a modification of the linkage system shown in Patent No. 1,897,689 for Actuating mechanism for garment pressing machines and Patent No. 2,026,-264 for Garment pressing machine, in association with the fluid motor 38, wherein one link 202 is pivotable on one fulcrum 204 to bring said members to pressing position with relatively light pressure and automatically pivotable after a predetermined amount of its movement on a different fulcrum 206 to apply a greater ironing pressure to said pressing members. Means are provided actuated by said linkage to move the latch 200 to a position overlying the outer end 150 of the operating lever or control member 62 substantially at the instant the pressing members 22 and 24 are brought into pressing position and the fulcrum of the link 202 has changed from 204 to 206 ceasing the application of relatively light pressure to said pressing members 22 and 24 through the fulcrum 204 and initiating the period of heavy ironing pressure to said pressing members through the fulcrum 206. It is then obvious that as the outer portion 150 of said operating lever 62 is then brought to a position underlying the latch 200, the device will be held in a position supplying fluid to said fluid motor to exert greater predetermined ironing pressure and permitting release of the handles 192 and that the latch 200 will only take effect when both handles are released together. It is then obvious that if one of said handles 192 only be moved, as shown in Fig. 4 in dotted lines, that it will function to knock the outer end 150 of the operating lever or control member 62 free of said latch 200 to permit self-closing of said inlet valve 44 in the manner explained and immediate actuation of said trigger exhaust valve 46 to cause immediate relative separation of said pressing members 22 and 24. It is obvious that so far as the means preferably comprising latch means for holding the master valve or inlet valve open to actuate the fluid motor 38 is concerned, that any type of control means for moving the outer end 150 of the operating lever or control member 62 may be employed, but that greater safety

can be effected if the pair of handles 192 hitherto described be employed, operable when both are moved to actuate the fluid motor to bring the pressing members into pressing juxtaposition and operable when one only is moved to evacuate the fluid motor to permit the separation of said pressing members. Inasmuch as all of these safety features are preferably employed together, I will now describe in detail the specific type of handles, specific type of linkage and the specific type of latching means preferably employed by me.

As stated hitherto, means are provided to depress the outer end 150 of said operating lever or control member 62 to raise said inlet valve stem member 54 through the medium of the disk 106 against the pressure of the spring 116 to raise said inlet valve stem 54 to abut said inlet valve 44 to open the inlet valve to permit flow of fluid to the fluid motor 38 and to permit self-closing of said exhaust valve 46, to cause said fluid motor 38 and linkage 40 where employed, to relatively move said pressing members 22 and 24 to said closed pressing position. Said means includes a pair of cams 208 having upwardly tapered inner edges 210 forming, when in raised position, a crotch 212 between them in which the outer end 150 of the operating lever or control member 62 is adapted to lie with the overlapping inner cam ends normally overlying said outer end 150 when it is in its raised position. Said cams are each mounted on respective arms 214 projecting forwardly from and pivotally mounted on the master control valve 52 as at 215. The pair of control handles 192 is provided, each extending underneath the front end of the table 26 and each connected to a pivotally mounted cam arm 214 in the manner diagrammatically shown in Figs. 1-4 by the link 216, or specifically as shown in Figs. 9 and 10 by an arm 216 having the lower end thereof engaged within a suitable groove 218 in said cam arm 214. With this construction, it is obvious that when both said handles 192 are raised, said cams 208 are conjointly lowered to depress the outer end 150 of the lever or control member 62 in the crotch 212 between them to move said stem member 54 to open the inlet valve 44 and permit self-closing of said exhaust valve 46 to cause flow of fluid to said fluid motor 38 to relatively move said pressing members to closed position. It is also obvious that when either handle 192 is raised alone, no crotch 212 will be provided to become effective to lower the outer end 150 of the operating lever or control member, but that the operating lever end 150 will be merely pivoted sidewise so that the spring 116 may function to maintain or move the control member 54 and operating lever in or to a closed position closing the inlet valve and opening the exhaust valve to evacuate the fluid motor 38 to permit the weighted arm 36 to raise the pressing head 24 to open position.

As stated hitherto, I also provide the latch means 200 effective to latch the outer end 150 of the operating lever 62 in a depressed open position maintaining the inlet valve 44 open and the exhaust valve 46 closed to continue to apply fluid pressure to the fluid motor 38 as shown in Fig. 3 to apply the ironing pressure. As stated hitherto, said latch means 200 is arranged to become effective to engage the outer end 150 of the operating lever or control member 62 substantially at the instant that the pressing members 22 and 24 have been moved up to a pressing position. The latch

200 is thus pivotal on the pivot 201 from a position free of the outer end 150 of said operating lever or control member 62 as shown in Fig. 1 to a position overlying said operating end as shown in Figs. 2 and 3 after said pressing members have been brought to a pressing position, in the preferred embodiment shown, substantially when the link 202 has changed its fulcrum from 204 to 206 to apply the greater ironing pressure. As stated, I employ means actuated by said actuating means including the linkage 40 and fluid motor 38, in my preferred embodiment, comprising a link 220 connected to said linkage 40 adapted when said pressing members 22 and 24 approach their closed pressing position, to permit pivotal movement of said latch 200 to a position overlying the lowermost position of the outer end 150 of said operating lever 62 to retain said members 22 and 24 in closed pressing position during the application of said predetermined ironing pressure. In the preferred embodiment, the link 220 is provided with a boss 222 adapted to abut a pin 224 projecting laterally from the weight arm 226 of the latch 200. In the embodiment shown, it is obvious that when either handle 192 is raised alone as shown in dotted lines in Fig. 4, that the respective cam surface 210 will knock the outer end 150 of the operating lever 62 laterally free of the latch 200 to permit the spring 116 to immediately raise the outer end 150 of the operating lever or control member and to lower the stem member 54 to permit self-closing of the inlet valve 44 and to open the exhaust valve 46. It is obvious that when the latch 200 has functioned to overlie the depressed outer end 150 of the operating lever or control member after the handles 192 have been simultaneously actuated to simultaneously depress the cams 208 to lower the outer end 150 of the operating lever in the crotch between them, that said latch 200 will function to retain said outer end in depressed position opening the inlet valve 44 and permitting closing of the exhaust valve 46 to continuously apply fluid pressure to the fluid motor, and where the link 202 is employed, with greater pressure, for the desired ironing interval. It is obvious that when the inlet valve 44 is closed and the trigger exhaust valve 46 opened on raising of the outer end 150 of the operating lever that the flush valve 48, where employed, will function to quickly evacuate the fluid motor to permit the weight arm 36 to raise the pressing head 24 away from the pressing buck 22. As stated, any means may be provided to release the latch 200 from the outer end 150 of the operating lever or control member 62 and for this purpose I may provide a supplemental foot lever 228 to actuate a link 230 to raise the latch arm 226 to pivot the latch 200 free of the outer end 150 of said operating lever 62, such means being alternative or supplemental to the means previously described for unlatching the latch.

It is apparent that with the construction hitherto described, the latch 200 is gravity actuated by the weight of the weight arm 226 thereof and that the link 220 abutting the pin 224 of said weight arm 226 prevents the latch from being moved into latching position until the pressing members 22 and 24 have substantially reached a closed pressing position when the link 220 will have been lowered to the position shown in Fig. 3 by the respective movements of the parts of the linkage 40 caused by actuation of the fluid motor 38. It is apparent that with this construction a sharp gravity actuation of the latch 200 will be provided, sharper than where the locking of the mechanism is di-

rectly actuated by fluid pressure from the cylinder 38 or by the motion transmitting mechanism from the cylinder 38 to the pressing head 24. If desired, however, the device may be directly actuated by the fluid pressure from said cylinder 38 by 5 means of having the latch positively connected to the link 220, as by the spring 225 projecting upwardly from said link 220 to overlie the pin 224 and retain it in a position at all times immediately overlying the upper surface of said link 220, as 10 shown in Fig. 12. With this spring construction, as shown in Fig. 13, it is obvious that the spring 225 may yield to prevent jamming and consequent breaking of parts, should the point of the latch abut the end 150 of the operating lever or 15 control member during its pivotal movement. The embodiment of latch, I have shown in Figs. 1-4 will also not jam, the latch itself merely tilting should its point abut the end 150 of the operating lever 62 during its pivotal movement, and 20 it is apparent that in both the embodiment shown in Figs. 12 and 13 and the embodiment shown in Figs. 1-4 that I have provided jam-proof structures.

In place of the latch means 200 automatically 25 operated by said actuating means when said pressing members are brought into pressing juxtaposition to permit release of said handles while said controlling means continues to function to permit further actuation of said fluid motor to apply said ironing pressure, any other type of latching means may be employed for this purpose, such as the type of means shown in my copending application, S. N. 376,286, filed January 28, 1941, for Control means for pressing machines, 30 effective to release similar respective handles while the ironing pressure is being applied and in addition any suitable type of means to evacuate the fluid motor may be employed, such as the means shown in said application. It is immaterial whether said latching means be controlled by the linkage as shown herein, or be controlled by the rising of the pivoted cylinder as shown in 35 said application, by movement of the pressing head, by the flow of fluid, or otherwise. If desired, any suitable means and manually operated control therefor may be employed to evacuate the fluid motor other than the specific type shown.

I have also shown in Fig. 12 a structure analogous to that shown in said copending application, wherein the cylinder 246 of the fluid motor 38 itself actuates the link 220 in place of having the movement thereof controlled by the motion transmitting mechanism or linkage 40. In this construction, the link 220 is not pivoted on the same pivot as the latch 200, but is pivoted at the point 231 as a lever of the first class. The rear end of said link 220 is pivotally attached to a rod 233 having an elongated slot 235 at the lower end thereof receiving a pin 237 projecting laterally from said cylinder, the slot 235 being of such a length as to become operative to tilt the front end 239 of the link 220 downwardly when the cylinder 246 has been actuated substantially far enough to substantially close said pressing members 22 and 24.

I have shown in Fig. 11 a pair of an alternative type of handles 192', each effective to axially move a wire 196 encased in a flexible armored cable 198 to raise a respective rod 232 to abut a respective arm 234 projecting rearwardly from a cam arm 214, to lower the respective cams 208 together when both of the respective buttons or handles 192' are depressed together to lower the outer end 150 of said operating lever or control 70

member 62 to effect flow of fluid to the fluid motor 38 and also operative when a single button 192' is moved alone to raise a respective rod 232 as shown, to depress a single cam 208 to free the outer end 150 of said operating lever 62 from the latch 200 to permit a quick evacuation of said fluid motor 38 for separation of said pressing members 22 and 24. In the embodiment shown, each operating handle 192' comprises a socket 241 having a stem 236 projecting downwardly through a bore 238 therein connected to an end 240 of the axially movable wire 196, said button or handle 192' being normally urged to a raised position by a spring 242 contained in said socket 241 underneath said button 192'. While I have shown in Fig. 11 the operating buttons 192' and the cable encased axially movable wires 196 as an alternative construction to the handles 192 shown in Figs. 1-10, it is obvious that this particular structure of cable encased axially movable wire 196 may be readily employed for any purpose of remote control in a pressing machine.

Employing the specific construction of the cams as shown, regardless of whatever type of actuating handle may be employed therefor, it is apparent that movement of either handle alone before or after latching will function to release the press, the depression of one handle alone prior to latching causing the end 150 of the operating lever or control member 62 to ride up the single cam surface and the actuation of a single handle after latching, similarly functioning to permit the spring 116 to urge the outer end 150 of the operating lever or control member 62 upwards, the respective cam surface in this instance also functioning to move said end 150 of the operating lever 62 laterally free of said latch to permit said spring 116 to force it upwards along said cam surface. It is obvious that the specific structure of the internal wall 144 of the exhaust branch port 142 permits and limits the necessary movements of the end 150 of the operating lever 62 for this purpose.

I have shown in Fig. 1 my device in a static position with the pressing members in relatively open position. When both operating handles 192 are moved, as shown in Fig. 2, the outer end 150 of the operating lever or control member will be lowered by the cams 208 to raise the stem member 54 to open the inlet valve 44 against the pressure of the springs 116 and 98 and raise the disk 106 free of the exhaust valve stem 132 to permit self-closing of said trigger exhaust valve 46. As a passage is now open through the passage means 66 and pipe 60 to the flush valve 48, the pressure in the inlet pipe 58 will further compress the spring 98 to permit the socket 84 to slide to open the check valve 50 to permit fluid to be passed to the flush valve 48 as indicated in Fig. 2 by the arrows. Fluid flowing through the inlet port 162 of the flush valve 48 will then jointly raise the inlet valve 170 and differential valve 172 and lift the connecting valve stem 184 and connected exhaust valve 168 to close the exhaust port 166. Sustained pressure through said inlet line will then raise the differential valve 172 free of the ducts 186 compressing the spring 190 for this purpose so as to permit flow of fluid through the flush valve 48 out the outlet port 164 thereof and pipe 180 to the fluid motor 38 pivotally mounted on the pivot pin 244 on the front end of the machine frame 28. The fluid motor 38 comprises the cylinder 246 pivotally mounted as at 244 on said frame and the piston head 248 axially movable in said cylinder to actuate the

piston rod 250 connected to the linkage 40. The flow of fluid to the fluid motor 38 will urge the piston rod 250 outwards, the link 202 functioning on its fulcrum 204 to move the pressing head 24 rapidly towards the buck with light pressure. When the parts have assumed the position shown in Fig. 2, the latch 200 will overlie the outer end 150 of the operating lever 62. The link 202 actuated by the linkage 40 will be withdrawn from the latch 200 substantially at the instant shown in Fig. 2 when the pressing head is brought into pressing juxtaposition with the buck 22 to permit instant gravity actuation of the latch 200 to latch the outer end 150 of the operating lever or control member 62 in this position to permit release of the handles 192 as shown in Fig. 3 with said latch then retaining the master valve 52 and flush valve 48 in a position permitting the ingress of supplemental fluid to said fluid motor 38 to urge the piston thereof to the position shown in Fig. 3, the link 202 pivoting on the point 206 as a fulcrum to apply the ironing pressure. When the piston 248 has reached the outer end of its stroke in the cylinder, the differential valve 172 in the flush valve will then be lowered by the spring 190 due to a substantial equalization of pressure in the cylinder 248 and inlet line 42, to cause said valve 172 to function as a check valve.

When it is desired to release the pressing members, one handle 192 may be raised as shown in dotted lines in Fig. 4 to permit the cam surface 210 thereof to knock the outer end 150 of said operating lever or control member 62 laterally free of the latch 200 as shown in the dotted line mid position shown in Fig. 4, permitting the spring 116 to urge the control member 54 downwards and rapidly raise the outer end 150 of said operating lever or control member to its upper static position. As the valve stem member 54 is urged downwards, it is apparent that the disk 166 thereof will abut the exhaust valve stem 134 to tilt the exhaust valve 48 to the open position shown and that the stem member 54 will be lowered free of the inlet valve 44 so that the spring 38 will immediately function to close the inlet valve 44 and substantially simultaneously close the check valve 50. As pressure in the master valve 52 is released by the trigger exhaust valve 48, pressure will fall in the pipe 60 in such a degree as to permit the spring 190 in the exhaust valve 48 to urge the differential valve 172 to close the inlet vent means 186 in said inlet valve 170 and said fluid pressure will force the inlet valve 170, the connected valve stem 184 and exhaust valve 168 to open the exhaust port 166 in the flush valve 48 permitting the rapid discharge of fluid from the cylinder 248 backwards through the connecting pipe 180 and out through the exhaust port 166 to permit the weighted lever arm 36 to lower the linkage 40 to move the piston 248 within the cylinder 248 to exhaust the fluid out of the fluid motor 38 and out said exhaust port 166.

It is thus apparent that I have provided a novel type of safety control for pressing or other machines preferably one employing a fluid motor with the advantages described above.

It is understood that my invention is not limited to the specific embodiments shown and that various deviations may be made therefrom without departing from the spirit and scope of the appended claims.

What I claim is:

1. In a pressing machine, relatively movable pressing members, a fluid motor for bringing said members into pressing juxtaposition, means for

controlling the flow of fluid to said fluid motor including a universally mounted control member normally urged to a position exhausting said fluid motor movable to a position permitting flow to said fluid motor, a pair of manually operable means, means actuated by each of said manually operable means to apply an oblique force in a forward direction to said universally mounted control member, obliquely opposite to the force applied by said other means, adapted, when both manually operable means are actuated together to move said universally mounted control member forwardly to actuate said controlling means to permit flow to said motor; and when one of said manually operable means only is actuated, to move said universally mounted control member obliquely to permit return of said controlling means to a position exhausting said fluid motor, to separate said pressing members.

2. In a pressing machine, relatively movable pressing members, a motor for bringing said members into pressing juxtaposition, means for controlling said motor including a universally mounted control member normally urged to a position shutting off said motor movable to a position actuating said motor, a pair of manually operable means, means actuated by each of said manually operable means to apply an oblique force in a forward direction to said universally mounted control member, obliquely opposite to the force applied by said other means, adapted, when both manually operable means are actuated together to move said universally mounted control member forwardly to actuate said motor; and when one of said manually operable means only is actuated, to move said universally mounted control member obliquely to permit return of said controlling means to a position shutting off said motor, to separate said pressing members.

3. In a pressing machine, having a table, guard means projecting downwardly from the table, relatively movable pressing members, a motor for bringing said members into pressing juxtaposition, means for controlling said motor including a universally mounted control member normally urged to a position shutting off said motor movable to a position actuating said motor, a pair of manually operable means mounted and operative from below the front end of said table behind said guard means, means actuated by each of said manually operable means to apply an oblique force in a forward direction to said universally mounted control member, obliquely opposite to the force applied by said other means, adapted, when both manually operable means are actuated together to move said universally mounted control member forwardly to actuate said motor; and when one of said manually operable means only is actuated, to move said universally mounted control member obliquely to permit return of said controlling means to a position shutting off said motor, to separate said pressing members.

4. In a pressing machine, relatively movable pressing members, actuating means to relatively move said pressing members to a pressing position and thereafter apply pressure, including a fluid motor, means for controlling the flow of fluid to said fluid motor including a universally mounted control member normally urged to a position exhausting said fluid motor, movable to a position to actuate said controlling means to permit flow to said fluid motor, a pair of manually operable means, means actuated by each of said manually operable means to apply an oblique force in a forward direction to said uni-

versally mounted control member, obliquely opposite to the force applied by said other means, adapted, when both manually operable means are actuated together to move said universally mounted control member forwardly to actuate said controlling means to permit flow to said motor; and when one of said manually operable means only is actuated, to move said universally mounted control member obliquely to permit return of said controlling means to a position exhausting said fluid motor, to separate said pressing members, and latch means automatically controlled by said actuating means to latch said movable control member in a position actuating said fluid motor when said pressing members are brought into pressing juxtaposition to permit release of said manually operable means while said movable control member continues to function to permit further actuation of said fluid motor to apply said pressure, inoperable when a single oblique force applying means has been actuated by its respective manually operable means to knock said universally mounted control member from said latch means.

5. In a pressing machine, relatively movable pressing members, actuating means to relatively move said pressing members to a pressing position and thereafter apply pressure, including a fluid motor, means for controlling the flow of fluid to said fluid motor including a universally mounted control member normally urged to a position exhausting said fluid motor movable to a position to actuate said controlling means to permit flow to said fluid motor, a pair of manually operable means, means actuated by each of said manually operable means to apply an oblique force in a forward direction to said universally mounted control member, obliquely opposite to the force applied by said other means, adapted, when both manually operable means are actuated together to move said universally mounted control member forwardly to actuate said controlling means to permit flow to said motor; and when one of said manually operable means only is actuated, to move said universally mounted control member obliquely to permit return of said controlling means to a position exhausting said fluid motor, to separate said pressing members, and latch means automatically controlled by said actuating means to latch said movable control member in a position actuating said fluid motor operative only on the joint release of said manually operable means after said pressing members have been brought into pressing juxtaposition on continued joint actuation of both of said manually operable means to thereafter permit release of said manually operable means while said movable control member continues to function to permit further actuation of said fluid motor to apply said pressure, inoperable when a single oblique force applying means has been actuated by its respective manually operable means to knock said universally mounted control member from said latch means.

6. In a pressing machine, relatively movable pressing members, actuating means to relatively move said pressing members to a pressing position and thereafter apply pressure, including a fluid motor, means for controlling the flow of fluid to said fluid motor including a universally mounted control member normally urged to a position exhausting said fluid motor movable to a position to actuate said controlling means to permit flow to said fluid motor, a pair of manually operable means, means actuated by each of said

manually operable means to apply an oblique force in a forward direction to said universally mounted control member, obliquely opposite to the force applied by said other means, adapted, when both manually operable means are actuated together to move said universally mounted control member forwardly to actuate said controlling means to permit flow to said motor; and when one of said manually operable means only is actuated, to move said universally mounted control member obliquely to permit return of said controlling means to a position exhausting said fluid motor, to separate said pressing members, and latch means automatically moved by said actuating means to a position, after said pressing members have been brought into pressing juxtaposition on continued joint actuation of both of said manually operable means, so that the joint release of said manually operable means may permit said control member to abut said latch means while said movable control member continues to function to permit further actuation of said fluid motor to apply said pressure, and means to relatively move said movable control member free of said latch to exhaust said fluid motor to separate said pressing members.

7. In a pressing machine, relatively movable pressing members, actuating means to relatively move said pressing members to a pressing position and thereafter apply an ironing pressure, including a fluid motor, and means for controlling the flow of fluid to said fluid motor including a universally mounted control member normally urged to a position exhausting said fluid motor movable to a position to actuate said controlling means to permit flow to said fluid motor, a pair of manually operable means, means actuated by each of said manually operable means to apply an oblique force in a forward direction to said universally mounted control member, obliquely opposite to the force applied by said other means, adapted, when both manually operable means are actuated together to move said universally mounted control member forwardly to actuate said controlling means to permit flow to said motor; and when one of said manually operable means only is actuated, to move said universally mounted control member obliquely to permit return of said controlling means to a position exhausting said fluid motor, to separate said pressing members, and means automatically controlled by said actuating means operative only on the joint release of said manually operable means after said pressing members have been brought into pressing juxtaposition on continued joint actuation of both of said manually operable means to thereafter permit release of said manually operable means while said controlling means continues to function to permit further actuation of said fluid motor to apply said ironing pressure.

8. In a garment pressing machine, relatively movable pressing members, actuating means to relatively move said pressing members to a pressing position and thereafter apply an ironing pressure, including a fluid motor, means for controlling the flow of fluid to said fluid motor, including a movable control member normally urged to a position exhausting said fluid motor and manually actuated means for moving said movable control member to a position to admit fluid to said fluid motor to relatively move said pressing members to pressing juxtaposition and apply pressure on a single movement of said manually actuated means, and gravity actuated latch means automatically controlled by said actuating

means to become effective to move into a position permitting latching of said movable control member in said actuating position only on release of said manually actuated means after said pressing members have been brought into pressing juxtaposition when said controlling means may continue to function to permit further actuation of said fluid motor to apply said ironing pressure.

9. In a garment pressing machine, a frame, a table mounted on said frame, relatively movable pressing members, actuating means to relatively move said members to a pressing position and thereafter apply an ironing pressure including a fluid motor, means for controlling the flow of fluid to said fluid motor including a movable control member normally urged to a raised position exhausting said fluid motor and means to move said movable control member to supply fluid to said fluid motor to cause said fluid motor and actuating means to relatively move said pressing members to pressing position and to retain said members in said pressing position during the application of said ironing pressure, comprising a latch pivotally mounted on said frame weighted to pivot by gravity to an operative position overlying a portion of said movable control member when in actuating position, a pair of cams having downwardly tapering inner edges having overlapping inner ends normally overlying said portion of said control member when in a raised position exhausting said fluid motor, each mounted on an arm projecting forwardly from and pivotally mounted on the front of said pressing machine frame, a pair of control handles extending underneath the front end of said table pivotally mounted on said machine frame and each connected to a pivotally mounted cam arm so that when both handles are raised said cams may be conjointly lowered to depress said portion of the control member in the crotch between them to cause flow of fluid to said fluid motor to relatively move said pressing members to closed position and when either handle is raised alone the cam actuated thereby may function to knock the outer end of said control member laterally to effect movement thereof to a position permitting said pressing members to pivot to open position discharging said fluid from said fluid motor.

10. In a garment pressing machine, a frame, a table mounted on said frame, relatively movable pressing members, actuating means to relatively move said members to a pressing position and thereafter apply an ironing pressure including a fluid motor, means for controlling the flow of fluid

to said fluid motor including a movable control member normally urged to a raised position exhausting said fluid motor and means to move said movable control member to supply fluid to said fluid motor to cause said fluid motor and actuating means to relatively move said pressing members to pressing position, comprising a pair of cams having downwardly tapering inner edges having overlapping inner ends normally overlying a portion of said control member when in a raised position, each mounted on an arm projecting forwardly from and pivotally mounted on the front of said pressing machine frame, a pair of control handles extending underneath the front end of said table pivotally mounted on said machine frame and each connected to a pivotally mounted cam arm so that when both handles are raised said cams may be conjointly lowered to depress said portion of the control member in the crotch between them to cause flow of fluid to said fluid motor to relatively move said pressing members to closed position and when either handle is raised alone the cam actuated thereby may function to knock the outer end of said control member laterally to effect movement thereof to a position permitting said pressing members to pivot to open position discharging said fluid from said fluid motor.

11. In a garment pressing machine, a frame, relatively movable pressing members, actuating means to relatively move said members to a pressing position and thereafter apply an ironing pressure including a fluid motor, means for controlling the flow of fluid to said fluid motor including a movable control member normally urged to a position exhausting said fluid motor and means to move said movable control member to supply fluid to said fluid motor to cause said fluid motor and actuating means to relatively move said pressing members to pressing position and to retain said members in said pressing position during the application of said ironing pressure, comprising, a latch pivotally mounted on said frame weighted to pivot by gravity to an operative position overlying a portion of said movable control member when in actuating position, manually actuated means to depress said portion of the control member to cause flow of fluid to said fluid motor to relatively move said pressing members to closed position, means normally pivoting said latch to a position free of the pivotal movement of said portion of said control member actuated by said actuating means when said pressing members approach their pressing position to free said latch for the gravity actuated pivotal movement thereof to a position overlying the lowermost position of said portion of said control member and to abut said portion on joint release of said handles to retain said members in pressing position during the application of ironing pressure while permitting release of said handles, raising of either handle alone being also operative to cause its respective cam to knock said portion of said control member laterally free of said latch when in latched position to effect movement thereof to a position permitting said pressing members to pivot to open position discharging said fluid from said fluid motor.

12. In a garment pressing machine, a frame, a table mounted on said frame, relatively movable pressing members, actuating means to relatively move said members to a pressing position and thereafter apply an ironing pressure including a fluid motor, means for controlling the flow of fluid to said fluid motor including a movable con-

trol member normally urged to a raised position exhausting said fluid motor and means to move said movable control member to supply fluid to said fluid motor to cause said fluid motor and actuating means to relatively move said pressing members to pressing position, comprising a pair of pivotally mounted cams having downwardly tapering inner edges having overlapping inner ends normally overlying a portion of said control member when in a raised position, a pair of control buttons one for each hand on the front end of said table, flexible cable encased axially movable wires connecting said buttons and cams to selectively move said cams so that when both buttons are depressed, said cams may be conjointly lowered to depress said portion of the control member in the crotch between them to cause flow of fluid to said fluid motor to relatively move said pressing members to closed position and when either button is depressed alone the cam actuated thereby may function to knock the outer end of said control member laterally to effect movement thereof to a position permitting said pressing members to pivot to open position discharging said fluid from said fluid motor.

13. In a pressing machine, relatively movable pressing members, actuating means to relatively move said pressing members to a pressing position and thereafter apply pressure, including a fluid motor, means for controlling the flow of fluid to said fluid motor including a universally mounted control member normally urged to a position exhausting said fluid motor movable to a position to actuate said controlling means to permit flow to said fluid motor, a pair of manually operable means, means actuated by each of said manually operable means to apply an oblique force in a forward direction to said universally mounted control member, obliquely opposite to the force applied by said other means, adapted, when both manually operable means are actuated together to move said universally mounted control member forwardly to actuate said controlling means to permit flow to said motor; and when one of said manually operable means only is actuated, to move said universally mounted control member obliquely to permit return of said controlling means to a position exhausting said fluid motor, to separate said pressing members and latch means automatically operative to latch said movable control member in a position actuating said fluid motor when said pressing members are brought into pressing juxtaposition to permit release of said manually operable means while said movable control member continues to function to permit further actuation of said fluid motor to apply said pressure, inoperable when a single oblique force applying means has been actuated by its respective manually operable means to knock said universally mounted control member from said latch means.

14. In a pressing machine, relatively movable pressing members, actuating means to relatively move said pressing members to a pressing position and thereafter apply pressure, including a fluid motor, means for controlling the flow of fluid to said fluid motor including a universally mounted control member normally urged to a position exhausting said fluid motor movable to a position to actuate said controlling means to permit flow to said fluid motor, a pair of manually operable means, means actuated by each of said manually operable means to apply an oblique force in a forward direction to said universally mounted control member, obliquely opposite to

the force applied by said other means, adapted, when both manually operable means are actuated together to move said universally mounted control member forwardly to actuate said controlling means to permit flow to said motor; and when one of said manually operable means only is actuated, to move said universally mounted control member obliquely to permit return of said controlling means to a position exhausting said fluid motor, to separate said pressing members, and latch means automatically operative to latch said movable control member in a position actuating said fluid motor operative only on the joint release of said manually operable means after said pressing members have been brought into pressing juxtaposition on continued joint actuation of both said manually operable means to thereafter permit release of said manually operable means while said movable control member continues to function to permit further actuation of said fluid motor to apply said pressure, inoperable when a single oblique force applying means has been actuated by its respective manually operable means to knock said universally mounted control member from said latch means.

15. In a garment pressing machine, relatively movable pressing members, actuating means to relatively move said pressing members to a pressing position and thereafter apply an ironing pressure, including a fluid motor, means for controlling the flow of fluid to said fluid motor, including a movable control member and manually actuated means for moving said movable control member to a position to admit fluid to said fluid motor to relatively move said pressing members to pressing juxtaposition and apply pressure on a single movement of said manually actuated means, and latch means automatically operative to latch said movable control member in said position only after said pressing members have been brought into pressing juxtaposition to permit release of said manually actuated means while said controlling means continues to function to permit further actuation of said fluid motor to apply said ironing pressure.

16. In a garment pressing machine, a frame, a table mounted on said frame, relatively movable pressing members, actuating means to relatively move said members to a pressing position and thereafter apply an ironing pressure including a fluid motor, means for controlling the flow of fluid to said fluid motor including a movable control member normally urged to a raised position exhausting said fluid motor and means to move said movable control member to supply fluid to said fluid motor to cause said fluid motor and actuating means to relatively move said pressing members to pressing position, comprising a pair of cams having downwardly tapering inner edges having overlapping inner ends normally overlying a portion of said control member when in a raised position, each mounted on an arm projecting forwardly from and pivotally mounted on the front of said pressing machine frame, a pair of control handles extending underneath the front end of said table pivotally mounted on said machine frame and each connected to a pivotally mounted cam arm so that when both handles are raised said cams may be conjointly lowered to depress said portion of the control member in the crotch between them to cause flow of fluid to said fluid motor to relatively move said pressing members to closed position and latch means effective to latch said movable control member in depressed position to permit release of said handles

during the application of ironing pressure and when either handle is raised alone the cam actuated thereby may function to relatively move said control member free of said latch to effect movement thereof to a position permitting said pressing members to pivot to open position discharging said fluid from said fluid motor.

17. In a pressing machine, relatively movable pressing members, a motor for bringing said members into pressing juxtaposition, means for controlling said motor including a universally mounted control member normally urged to a position shutting off said motor movable to a position actuating said motor, a pair of manually operable means, and means actuated by each of said manually operable means to move obliquely forwardly and inwardly relative to said universally mounted member in opposite directions, adapted, when both manually operable means are actuated together to form a crotch to abut and move said control member to actuate said motor; and when one of said manually operable means only is actuated, to move said universally mounted control member obliquely to permit return of said controlling means to a position shutting off said motor, to separate said pressing members.

18. In a high speed garment pressing machine, relatively movable pressing members, actuating means including a fluid motor for bringing said members into garment pressing juxtaposition and thereafter applying an ironing pressure, means for controlling the flow of fluid to said fluid motor including a feed line for said fluid motor, a master control valve interposed in said feed line having a chamber, an inlet line connecting said chamber with a source of fluid pressure supply, an outlet line connecting said chamber with said fluid motor, a self-closing inlet valve at the inlet port of said chamber normally urged to a closed position, a self-closing exhaust valve in said chamber, a single stem member axially movable in said chamber normally urged to a closed axial position in said chamber permitting self-closing of said inlet valve and retaining said exhaust valve in open position movable axially to an open position opening said inlet valve and permitting self-closing of said exhaust valve, and a universally mounted control member normally urged by said stem member to a closed position movable from without said master control valve to move said stem member to said open position, a pair of manually operable means, means actuated by each of said manually operable means to apply an oblique force in a forward direction to said universally mounted control member, obliquely opposite to the force applied by said other means, adapted, when both manually operable means are actuated together to move said universally mounted control member forwardly to actuate said controlling means to permit flow to said motor; and when one of said manually operable means only is actuated, to move said universally mounted control member obliquely to permit return of said controlling means to a position exhausting said fluid motor, to separate said garment pressing members, latch means automatically operative to latch said movable control member in a position actuating said fluid motor when said pressing members are brought into pressing juxtaposition to permit release of said manually operable means while said movable control member continues to function to permit further actuation of said fluid motor to apply said ironing pressure, inoperable when a

single oblique force applying means has been actuated by its respective manually operable means to knock said universally mounted control member from said latch means, and a quick acting flush valve in said feed line beyond said exhaust valve immediately adjacent the fluid motor automatically rapidly actuated to open position by a drop of pressure in said feed line caused by opening of said exhaust valve, for quickly separating said pressing members after each lay for the rapid arrangement of the next lay and automatically rapidly actuated to closed position by the flow of fluid through said feed line on opening of said inlet valve whereby said pair of manually operable means form the entire control elements of the pressing machine.

19. In a high speed garment pressing machine, relatively movable pressing members, actuating means including a fluid motor for bringing said members into garment pressing juxtaposition and thereafter maintaining an ironing pressure, means for controlling the flow of fluid to said fluid motor including a feed line for said fluid motor, a self-closing inlet valve in said feed line, a self-closing exhaust valve in said feed line and a single movable control member operative on movement thereof to effect opening of said inlet valve and closing of said exhaust valve substantially simultaneously and operative on a different movement thereof to effect closing of said inlet valve and opening of said exhaust valve substantially simultaneously, normally urged to said position closing said inlet valve and movable to said position opening said inlet valve, a pair of manually operable means, means actuated by each of said manually operable means to apply an oblique force in a forward direction to said control member, obliquely opposite to the force applied by said other means, adapted, when both manually operable means are actuated together to move said control member forwardly to actuate said controlling means to permit flow to said motor; and when one of said manually operable means only is actuated, to move said control member obliquely to permit return of said controlling means to a position exhausting said fluid motor, to separate said garment pressing members, latch means automatically operative to latch said movable control member in a position actuating said fluid motor when said pressing members are brought into pressing juxtaposition to permit release of said manually operable means while said movable control member continues to function to permit further actuation of said fluid motor to apply said ironing pressure, inoperable when a single oblique force applying means has been actuated by its respective manually operable means to knock said control member obliquely therefrom, and a quick acting flush valve in said feed line beyond said exhaust valve immediately adjacent the fluid motor automatically rapidly actuated to open position by a drop of pressure in said feed line caused by opening of said exhaust valve, for quickly separating said pressing members after each lay for the rapid arrangement of the next lay and automatically rapidly actuated to closed position by the flow of fluid through said feed line on opening of said inlet valve whereby said pair of manually operable means form the entire control elements of the pressing machine.

20. In a high speed garment pressing machine, relatively movable pressing members, actuating means including a fluid motor for bringing said members into garment pressing juxtaposition and

thereafter applying an ironing pressure, means for controlling the flow of fluid to said fluid motor including a feed line for said fluid motor, a master control valve interposed in said feed line having a chamber, an inlet line connecting said chamber with the source of fluid pressure supply, an outlet line connecting said chamber with said fluid motor, a self-closing inlet valve at the inlet port of said chamber normally urged to a closed position, a self-closing exhaust valve in said chamber, a single stem member axially movable in said chamber normally urged to a closed axial position in said chamber permitting self-closing of said inlet valve and retaining said exhaust valve in open position movable axially to an open position opening said inlet valve and permitting self-closing of said exhaust valve, and a universally mounted control member normally urged by said stem member to a closed position movable from without said master control valve to move said stem member to said open position, a pair of manually operable means, means actuated by each of said manually operable means to apply an oblique force in a forward direction to said universally mounted control member, obliquely opposite to the force applied by said other means, adapted, when both manually operable means are actuated together to move said universally mounted control member forwardly to actuate said controlling means to permit flow to said motor; and when one of said manually operable means only is actuated, to move said universally mounted control member obliquely to permit return of said controlling means to a position exhausting said fluid motor, to separate said garment pressing members, and latch means automatically operative to latch said movable control member in a position actuating said fluid motor when said pressing members are brought into pressing juxtaposition to permit release of said manually operable means while said movable control member continues to function to permit further actuation of said fluid motor to apply said ironing pressure, inoperable when a single oblique force applying means has been actuated by its respective manually operable means to knock said universally mounted control member from said latch means, whereby said pair of manually operable means form the entire control elements of the pressing machine.

21. In a high speed garment pressing machine, relatively movable pressing members, actuating means including a fluid motor for bringing said members into garment pressing juxtaposition and thereafter maintaining an ironing pressure, means for controlling the flow of fluid to said fluid motor including a feed line for said fluid motor, a self-closing inlet valve in said feed line, a self-closing exhaust valve in said feed line and a single movable control member operative on movement thereof to effect opening of said inlet valve and closing of said exhaust valve substantially simultaneously and operative on a different movement thereof to effect closing of said inlet valve and opening of said exhaust valve substantially simultaneously, normally urged to said position closing said inlet valve and movable to said position opening said inlet valve, a pair of manually operable means, means actuated by each of said manually operable means to apply an oblique force in a forward direction to said control member, obliquely opposite to the force applied by said other means, adapted, when both manually operable means are actuated together to move said control member forwardly to actu-

ate said controlling means to permit flow to said motor; and when one of said manually operable means only is actuated, to move said control member obliquely to permit return of said controlling means to a position exhausting said fluid motor, to separate said garment pressing members, and latch means automatically operative to latch said movable control member in a position actuating said fluid motor when said pressing members are brought into pressing juxtaposition to permit release of said manually operable means while said movable control member continues to function to permit further actuation of said fluid motor to apply said ironing pressure, inoperable when a single oblique force applying means has been actuated by its respective manually operable means to knock said control member obliquely therefrom, whereby said pair of manually operable means form the entire control elements of the pressing machine.

22. In a high speed garment pressing machine, relatively movable pressing members, actuating means including a fluid motor for bringing said members into garment pressing juxtaposition and thereafter applying an ironing pressure, means for controlling the flow of fluid to said fluid motor including a feed line for said fluid motor, a master control valve interposed in said feed line having a chamber, an inlet line connecting said chamber with the source of fluid pressure supply, an outlet line connecting said chamber with said fluid motor, a self-closing inlet valve at the inlet port of said chamber normally urged to a closed position, a self-closing exhaust valve in said chamber, a single stem member axially movable in said chamber normally urged to a closed axial position in said chamber permitting self-closing of said inlet valve and retaining said exhaust valve in open position movable axially to an open position opening said inlet valve and permitting self-closing of said exhaust valve, and a universally mounted control member normally urged by said stem member to a closed position movable from without said master control valve to move said stem member to said open position, a pair of manually operable means, and means actuated by each of said manually operable means to apply an oblique force in a forward direction to said universally mounted control member, obliquely opposite to the force applied by said other means, adapted, when both manually operable means are actuated together to move said universally mounted control member forwardly to actuate said controlling means to permit flow to said motor; and when one of said manually operable means only is actuated, to move said universally mounted control member obliquely to permit return of said controlling means to a position exhausting said fluid motor, to separate said garment pressing members, whereby said pair of manually operable means form the entire control elements of the pressing machine.

23. In a high speed garment pressing machine, relatively movable pressing members, actuating means including a fluid motor for bringing said members into garment pressing juxtaposition and thereafter maintaining an ironing pressure, means for controlling the flow of fluid to said fluid motor including a feed line for said fluid motor, a self-closing inlet valve in said feed line, a self-closing exhaust valve in said feed line and a single movable control member operative on movement thereof to effect opening of said inlet valve and closing of said exhaust valve substantially simultaneously and operative on a different movement

thereof to effect closing of said inlet valve and opening of said exhaust valve substantially simultaneously, normally urged to said position closing said inlet valve and movable to said position opening said inlet valve, a pair of manually operable means, and means actuated by each of said manually operable means to apply an oblique force in a forward direction to said control member, obliquely opposite to the force applied by said other means, adapted, when both manually operable means are actuated together to move said control member forwardly to actuate said controlling means to permit flow to said motor; and when one of said manually operable means only is actuated, to move said control member obliquely to permit return of said controlling means to a position exhausting said fluid motor, to separate said garment pressing members, whereby said pair of manually operable means form the entire control elements of the pressing machine.

24. In a high speed garment pressing machine, relatively movable pressing members, actuating means including a fluid motor for bringing said members into garment pressing juxtaposition and thereafter applying an ironing pressure, means for controlling the flow of fluid to said fluid motor including a feed line for said fluid motor, a master control valve interposed in said feed line having a chamber, an inlet line connecting said chamber with the source of fluid pressure supply, an outlet line connecting said chamber with said fluid motor, a self-closing inlet valve at the inlet port of said chamber normally urged to a closed position, a self-closing exhaust valve in said chamber, a single stem member axially movable in said chamber normally urged to a closed axial position in said chamber permitting self-closing of said inlet valve and retaining said exhaust valve in open position movable axially to an open position opening said inlet valve and permitting self-closing of said exhaust valve, and a universally mounted control member normally urged by said stem member to a closed position movable from without said master control valve to move said stem member to said open position, a pair of manually operable means, and means actuated by each of said manually operable means to apply an oblique force in a forward direction to said universally mounted control member, obliquely opposite to the force applied by said other means, adapted, when both manually operable means are actuated together to move said universally mounted control member forwardly to actuate said controlling means to permit flow to said motor; and when one of said manually operable means only is actuated, to move said universally mounted control member obliquely to permit return of said controlling means to a position exhausting said fluid motor, to separate said garment pressing members, and a quick acting flush valve in said feed line beyond said exhaust valve immediately adjacent the fluid motor automatically rapidly actuated to open position by a drop of pressure in said feed line caused by opening of said exhaust valve, for quickly separating said pressing members after each lay for the rapid arrangement of the next lay and automatically rapidly actuated to closed position by the flow of fluid through said feed line on opening of said inlet valve whereby said pair of manually operable means from the entire control elements of the pressing machine.

25. In a high speed garment pressing machine, relatively movable pressing members, actuating means including a fluid motor for bringing said

members into garment pressing juxtaposition and thereafter maintaining an ironing pressure, means for controlling the flow of fluid to said fluid motor including a feed line for said fluid motor, a self-closing inlet valve in said feed line, a self-closing exhaust valve in said feed line and a single movable control member operative on movement thereof to effect opening of said inlet valve and closing of said exhaust valve substantially simultaneously and operative on a different movement thereof to effect closing of said inlet valve and opening of said exhaust valve substantially simultaneously, normally urged to said position closing said inlet valve and movable to said position opening said inlet valve, a pair of manually operable means, and means actuated by each of said manually operable means to apply an oblique force in a forward direction to said control member, obliquely opposite to the force applied by said other means, adapted, when both manually operable means are actuated together to move said control member forwardly to actuate said controlling means to permit flow to said motor; and when one of said manually operable means only is actuated, to move said control member obliquely to permit return of said controlling means to a position exhausting said fluid motor, to separate said garment pressing members, and a quick acting flush valve in said feed line beyond said exhaust valve immediately adjacent the fluid motor automatically rapidly actuated to open position by a drop of pressure in said feed line caused by opening of said exhaust valve, for quickly separating said pressing members after each lay for the rapid arrangement of the next lay and automatically rapidly actuated to closed position by the flow of fluid through said feed line on opening of said inlet valve whereby said pair of manually operable means form the entire control elements of the pressing machine.

26. In a high speed garment pressing machine, relatively movable pressing members, actuating means including a fluid motor for bringing said members into garment pressing juxtaposition and thereafter maintaining an ironing pressure, means for controlling the flow of fluid to said fluid motor including a feed line for said fluid motor, a self-closing inlet valve in said feed line, a self-closing exhaust valve in said feed line and a single movable control member operative on movement thereof to effect opening of said inlet valve and closing of said exhaust valve substantially simultaneously and operative on a different movement thereof to effect closing of said inlet valve and opening of said exhaust valve substantially simultaneously, normally urged to said position closing said inlet valve and movable to said position opening said outlet valve, a pair of manually operable means, means actuated by each of said manually operable means to apply an oblique force in a forward direction to said control member, obliquely opposite to the force applied by said other means, adapted, when both manually operable means are actuated together to move said control member forwardly to actuate said controlling means to permit flow to said motor; and when one of said manually operable means only is actuated, to move said control member obliquely to permit return of said controlling means to a position exhausting said fluid motor, to separate said garment pressing members and gravity actuated latch means automatically controlled by said actuating means to become effec-

5 give to move into a position to permit it to latch said control member in said actuating position only on release of said manually operable means after said garment pressing members have been brought into pressing juxtaposition so that said controlling means may continue to function on further actuation of said fluid motor to apply

pressure, inoperable when a single oblique force applying means has been actuated by its respective manually operable means to knock said control member obliquely therefrom, whereby said pair of manually operable means form the entire control elements of the pressing machine.

FRANK C. LORNITZO.
